Inventor:
Oscar Carlson:

By Chas. C. Neuman
Atty.

UNITED STATES PATENT OFFICE.

OSCAR CARLSON, OF TAMPA, FLORIDA.

PAVING-BLOCK CUTTER.

Application filed April 18, 1923. Serial No. 632,878.

To all whom it may concern:

Be it known that I, OSCAR CARLSON, a citizen of the United States, residing at Tampa, in the county of Hillsborough and 5 State of Florida, have invented certain new and useful Improvements in a Paving-Block Cutter, of which the following is a specification.

This invention relates to improvements in 10 a machine of apparatus designed for use in the construction of streets, roads, and sidewalks, and has particular relation to an apparatus employed for cutting or trimming the paving blocks therefor, and especially, such blocks as are known to the 15 trade as "asphalt blocks," usually composed of a composition with asphalt forming a part thereof.

These blocks are each, generally, about 20 one foot long, five inches wide, and two and one-half inches thick, and in such sizes or dimensions are delivered to the paving contractor or road-builder for laying. In the construction of the roadways in which such 25 blocks are employed, as paving therefor, and particularly in the construction of streets and sidewalks, it is necessary, in joining the main body of the pavement to the curbs, to cut down the sizes of some of 30 the blocks, or to trim them so that they will fit or fill in the spaces properly between the body of the pavement and the curbs, as well as, at corners or angles of the roadway.

On account of the tenacity of the material 35 and other characteristics of the blocks, the cutting down of the size thereof, or trimming the same, has heretofore required much time and labor, usually of two men for cutting each block. Besides, the means and 40 methods heretofore commonly employed for cutting or trimming the blocks, have been found unsatisfactory, in that the blocks could not be accurately cut or shaped to fit the desired spaces without the expenditure 45 of much time and labor, and often without several efforts.

The principal object of the invention is to 50 provide a cutter for paving blocks and the like, which shall be simple and inexpensive in construction, strong, durable and efficient in operation, with its parts so made, arranged, and cooperating with one another, that the operation of cutting the blocks can be readily and accurately performed by one 55 person.

Other objects and advantages of the in-

vention will become apparent from the following description and explanation, which will be more readily understood, when read in conjunction with the accompanying drawing, which illustrates one embodiment of the invention, it being understood that various modifications may be resorted to without departing from the spirit of the invention so long as they come within the scope of the 65 appended claims forming a part hereof.

In the drawing,—

Figure 1 is a view in side elevation of a paving-block cutter embodying the invention, showing the parts thereof in about the 70 positions they will assume or occupy in the initial step of cutting a block.

Fig. 2 is a top plan view showing the hand lever of the device shortened for the convenience of illustration, and Fig. 3 is a front 75 end view showing the parts in about the positions illustrated in Fig. 1.

Like numerals of reference refer to like parts throughout the different views of the 80 drawings.

The reference numeral 5 designates as a whole the main or supporting frame of the apparatus, which is preferably triangular in shape as shown, and may be made of any suitable size and material. This frame is 85 provided at each of its corners with a caster or wheel 6 to enable the frame to be readily removed from one point to another and to support it in a steady manner.

Mounted on the upper surface of the 90 cross-piece 7 at the rear end of the frame 5, is a pair of spaced uprights 8 between which is movably mounted the knife-carrying lever 9 of the apparatus. This lever has at or near its rear end a transversely disposed bolt 10 which is employed to pivotally connect the lever 9 to a pair of links 11 one of which is located on each side of the lever 9 as is clearly shown in Figs. 1 and 2 of the drawings. The lower portion of each of the links 11 is provided with a plurality of openings 12 located one above the other for the purpose of permitting of adjustment of the lever 9 with respect to the hand 95 or operating lever 13 of the apparatus. This hand or operating lever is located between the uprights 8 near their upper ends and fulcrumed thereon by means of a bolt or pin 14. The rear portion of the lever 13 is extended between the upper portion of the links 11 and is pivotally connected thereto by means of a bolt or pin 15 trans-

versely mounted on the lever 13 in a suitable bearing therefor. The upper portion of each of the uprights 8 is provided with an opening 16, which openings register with 5 one another for the reception of the fulcrum 14, should it be desired to raise the fulcrum of the lever 13 or to adjust it with respect to the knife-carrying lever 9 which may be desirable under certain circumstances. The knife-carrying lever 9 is fulcrumed near its front end on an upright fulcrum member 17 which is preferably of an inverted U-shaped form and has its lower portions screw-threaded and extended 10 through vertical openings in the side pieces of the frame 5 near the front ends of said pieces. The upper portion of this fulcrum member 17 is horizontally disposed as shown in Figs. 2 and 3 and said portion is journaled in a suitable bearing 18 secured to the lower surface of the lever 9 near its front end. The front end of this lever is provided in its lower portion with a right angled recess 19 and has mounted on the 15 upper wall of said recess a depending cutter or knife 20 which is transversely disposed with respect to the lever 9 and is secured to said lever by means of a pair of angle iron clamping plates 21 which are secured at their bases to the lever 9, the knife or cutter 20 being interposed between said clamps, as is obvious and also clearly shown in Figs. 1 and 3 of the drawings.

Mounted on the front portion of the supporting frame 5 and extended upwardly therefrom is a support 22 for the lower cutter or knife 23 of the apparatus, which latter knife is extended transversely with respect to the support 22 and upwardly 20 therefrom at a suitable point to co-incide with the knife 20 when the front end of the lever 9 is depressed by applying downward pressure to the front end of the operating lever or handle. The knife 23 is clamped 25 between and secured to the support 22 by means of angle iron members 24 transversely secured on the upper surface of the support 22 which is shown in the form of a rectangular block. In front of the support or block 22 and mounted on the upper surface of the frame 5 is another supporting block 25 which as is clearly shown in Fig. 1 extends somewhat above the support 22. This last named supporting block 30 25 has secured to its front surface a plate 26 which is extended rearwardly over the upper end of the block 25 to a point near the knife 23 to form a rest 27 for the paving blocks as they are being positioned for the 35 cutting operation. This overlying rest or portion 27 of the plate 26 is resilient and normally occupies a position about like that shown in Fig. 1 so that a paving block can be mounted on the rest 27 without contacting 40 with the knife 23 until said paving block

is suitably adjusted on said rest. Vertically and pivotally secured at one of its ends to the supporting block 25 is a guide member 28 which overlies the supporting block 25 at its upper end and also overlies the rest 27 for the paving blocks. This guide member is provided with a transversely disposed slot 29 to receive a set screw 30 seated in the plate 26, by which arrangement it is manifest that the guide member 28 can be adjusted laterally with respect to the rest 27 so that the paving blocks can be properly positioned for the cutting operation of the apparatus.

From the foregoing and by reference to the drawing, it will be readily understood and clearly seen that as the hand or operating lever 13 extends at its front end to about the front end of the main frame, the said lever can be manipulated by the same person who applies the paving blocks to the rest 27 to be cut or trimmed. The operation of cutting the blocks is as follows:

A block is placed on the rest 27 and positioned thereon so that the desired amount of the block to be cut away will be determined by the position of the knives 20 and 23 with respect to the paving block, when by applying downward pressure to the front end of the operating lever 13, it is manifest that the knife-carrying lever 9 will be depressed at its front end, thereby causing the knives 20 and 23 to make incisions on opposite surfaces of the paving block and in alignment with each other so that if the block is not entirely severed by the knives, the uniting portion thereof can be readily broken. The fulcrum member 17 is adjustably mounted on the supporting frame 5 by means of the screw-threaded lower portions 95 of said member and nuts 31 and 32 which engage said members below and above the supporting frame respectively.

By my improvements it is apparent that as the hand lever is fulcrumed near its rear end and the knife carrying lever is fulcrumed near its front end, and as these levers are pivotally or loosely connected near their rear ends, great leverage will be afforded the knife or cutter 20 on the front end of the knife carrying lever, to the end that paving blocks may be cut or trimmed with a slight expenditure of pressure or power applied downwardly to the front end of the hand lever. It is further manifest that the fulcrum member 17 can be so adjusted on the supporting frame as to position the knives or cutters of the device closer together or further apart as may be required. It is also manifest that by providing the links 11 with the openings 12, and the uprights 8 with the openings 10, the levers 9 and 10 can be adjusted with respect to one another.

Having thus fully described my inven-

tion, what I claim as new and desire to secure by Letters Patent is:—

An apparatus of the class described including in combination with a main frame, 5 an upright support mounted thereon near one of its ends, a cutter mounted on said support transversely with respect to said frame, a spring plate mounted on said support and extended in the direction of said 10 cutter but normally above the horizontal plane of its free edge, a guide member adjustably mounted on the said support and overhanging the upper end thereof as well as a portion of said plate, another cutter transversely disposed with respect to the main frame above the first named cutter and movably mounted to coincide therewith, and means to raise and lower the last named cutter. 15

OSCAR CARLSON.
